UNITED STATES PATENT OFFICE

HARRY BEISER, OF DETROIT, MICHIGAN, ASSIGNOR TO OSCAR SHORR, OF DETROIT, MICHIGAN

CLEANING AND WASHING BRUSH

Application filed April 16, 1931. Serial No. 530,449.

My invention relates to an improvement in automobile cleaning and washing brushes.

One object of my invention is to provide a brush adapted to be connected with a garden 5 hose through which water is delivered to the brush.

The water discharge nozzle of the brush is embedded in its bristles, the latter completely surrounding the nozzle and projecting 19 beyond its free end to protect highly polished surfaces from injury, which might otherwise occur if the nozzle should contact therewith.

With the foregoing and other objects in view which will appear as the description 15 proceeds, the invention further resides in the combination and arrangement of parts and in the details of construction hereinafter described and claimed, it being understood that changes may be made in the precise embodiment of the invention herein disclosed without departing from the spirit of the same.

In the drawing accompanying this invention:

25 Figure 1 is a side elevation of the washing brush.

Figure 2 is a longitudinal sectional view of the same attached to a hose.

30 Figure 3 is a diagrammatic view of a fragment of the brush prior to coiling it upon the perforated end of the nozzle, forming a core for the brush.

Figure 4 is a diagrammatic view of a fragment of the perforated portion of the nozzle 35 in longitudinal section, showing a pair of twisted wires coiled thereon supporting the bristles forming the brush—the ends of the wires being secured to the nozzle.

Referring now to the letters of reference 40 placed upon the drawing:

A denotes a nozzle, provided at its outer end with a plurality of apertures A¹ for the discharge of water, its opposite end being screwed into a coupling member B, tapped 45 to receive a cooperating fitting C connecting it with a hose D, to which it is attached.

E denotes a rubber gasket to insure a watertight joint between the coupling members.

F indicates a handle preferably formed 50 of wood, sleeved upon the nozzle.

G denotes a thrust collar also sleeved upon the nozzle at the forward end of the handle having a cup-shaped socket bearing against the end of a brush H,—the bristles H¹ of which are held between a pair of twisted 55 wires H² coiled around the nozzle,—to deflect the bristles of the brush toward the forward end of the nozzle, thereby concealing it completely from view.

The twisted strands of wire supporting the 60 bristles may be secured to the nozzle in any suitable manner, for example the ends h may project through an opening in the nozzle, or they may be soldered thereto as indicated at h¹—see Figure 4.

Secured in the end of the nozzle is a small 65 brush I, which in combination with the main brush portion forms a pointed end to assist in guiding the brush into narrow or otherwise restricted openings.

The operation of the device will be readily 70 understood.

The nozzle is attached to a garden hose 75 through which water passes to the brush H upon opening a valve—not shown—controlling the delivery of water thereto. The operator applies the brush to the surface and as the water flows therethrough onto the surface to be cleaned, it quickly washes and rinses the surface thus reducing the time required 80 to obtain satisfactory results.

Having thus described my invention, what I claim is:

1. In a cleaning and washing brush, the combination of a pipe nozzle fitted at one end 85 with a coupling member for attachment to a cooperating hose coupling, said pipe nozzle being perforated at its forward end for the discharge of water; and a brush having bristles secured between a pair of twisted wires 90 coiled relatively close together around the nozzle, that the bristles may be massed and project radially from and longitudinally beyond the end of the nozzle, the ends of said pair of wires extending through a hole in the 95 nozzle and soldered to the nozzle to secure the brush thereon.

2. In a cleaning and washing brush, the combination of a pipe nozzle screw-threaded at one end to receive a hose coupling member, 100

said pipe nozzle perforated at its forward end for the discharge of water; an annular brush sleeved upon and secured to the perforated end of the nozzle, its radially disposed bristles concealing, inclosing and projecting longitudinally beyond the end of said nozzle, whereby the surface washed is protected from contact therewith; a cup shaped thrust collar sleeved on the nozzle adjacent the inner end of the brush, adapted to deflect said radially disposed bristles in a longitudinal direction, thereby massing the bristles closely around the nozzle and concealing it from view; a handle sleeved upon the nozzle 10 contacting at one end with the thrust collar; and a hose coupling member screwed upon the end of the nozzle, whereby upon adjustment, the handle is gripped between the thrust collar and the hose coupling member.

20 In testimony whereof, I sign this specification.

HARRY BEISSEER.
